Primary Examiner — Marianne Pandozzi*Assistant Examiner* — Jae Liang(74) *Attorney, Agent, or Firm* — Cooley LLP(57) **CLAIM**

The ornamental design for a smart water bottle, as shown and described.

DESCRIPTION

FIG. 1 is a perspective view of a smart water bottle showing our new design;

FIG. 2 is a front view thereof;

FIG. 3 is a back view thereof;

FIG. 4 is a side view thereof;

FIG. 5 is a top view thereof; and,

FIG. 6 is a bottom view thereof.

The broken lines in the drawings depict portions of the smart water bottle that form no part of the claimed design. The dash-dot lines in the drawing depict bounds of the claim that form no part of the claimed design.

1 Claim, 6 Drawing Sheets(56)
